(57) **CLAIM**

The ornamental design for an endoscope handle, as shown and described.

DESCRIPTION

The patent or application file contains at least one drawing executed in color. Copies of this patent or patent application publication with color drawing(s) will be provided by the Office upon request and payment of the necessary fee.

1. Endoscope handle

2. Endoscope handle

3. Endoscope handle

4. Endoscope handle

Fig. 1.1 is a perspective view of the new design of an endoscope handle according to first embodiment; fig. 1.2 is another perspective view thereof; fig. 1.3 is a front view thereof; fig. 1.4 is a rear view thereof; fig. 1.5 is a left view thereof; fig. 1.6 is a right view thereof; fig. 1.7 is a top view thereof; fig. 1.8 is a bottom view thereof; fig. 2.1 is a perspective view of the new design of an endoscope handle according to second embodiment; fig. 2.2 is another perspective view thereof; fig. 2.3 is a front view thereof; fig. 2.4 is a rear view thereof; fig. 2.5 is a left view thereof; fig. 2.6 is a right view thereof; fig. 2.7 is a top view thereof; fig. 2.8 is a bottom view thereof; fig. 3.1 is a perspective view of the new design of an endoscope handle according to third embodiment; fig. 3.2 is another perspective view thereof; fig. 3.3 is a front view thereof; fig. 3.4 is a rear view thereof; fig. 3.5 is a left view thereof; fig. 3.6 is a right view thereof; fig. 3.7 is a top view thereof; fig. 3.8 is a bottom view thereof; fig. 4.1 is a perspective view of the new design of an endoscope handle according to fourth embodiment; fig. 4.2 is another perspective view thereof; fig. 4.3 is a front view thereof; fig. 4.4 is a rear view thereof; fig. 4.5 is a left view thereof; fig. 4.6 is a right view thereof; fig. 4.7 is a top

(Continued)

view thereof; and fig. 4.8 is a bottom view thereof; the colors in the figures form no part of the claimed designs.
